UNITED STATES PATENT OFFICE.

KARL ZACK, OF DENVER, COLORADO.

RING.

1,250,070.

Specification of Letters Patent. Patented Dec. 11, 1917.

Application filed July 8, 1916. Serial No. 108,189.

To all whom it may concern:

Be it known that I, KARL ZACK, a citizen of the United States, residing at Denver, in the county of Denver and State of Colorado, 5 have invented certain new and useful Improvements in Rings; and I do hereby declare the following to be a full, clear, and exact description of the invention, such as will enable others skilled in the art to which

10 it appertains to make and use the same.

This invention relates to jewelry, and more especially to finger rings; and the object of the same is to produce a skeleton set ring capable of being worn alone or in combination with another ring, preferably plain, such as an ordinary wedding ring or a guard ring, which is inserted into the set ring from below. Hitherto it has been proposed to make a set ring in parts which were assembled or nested by inserting them from above, and slipping them all onto the finger when their rings or bands came into register, but such construction necessitated a division of the set and the ornament whereas when the 25 plain ring or guard ring is inserted from beneath the set or ornament may be in one piece and more artistic construction and design are thereby possible. It is well known that an ordinary wedding ring and an engagement ring are commonly worn side by side upon the same finger. The result is that the finger carries two rings whose bands are visible side by side, and this detracts from the beauty of an ornamental or 30 set ring besides occupying the larger space upon the finger.

Taking these facts into consideration, the object of the present invention is to provide a set ring with means for housing the plain 40 ring within it while not dividing the set or the ornament. This object is carried out in the manner hereinafter more fully described and claimed and as shown in the drawings wherein:—

45 Figure 1 is a top plan view of the complete ring, Fig. 2 a side elevation thereof, Fig. 3 an edge elevation thereof, and Fig. 4 is a bottom plan view; while Fig. 5 is a section on the line 5—5 of Fig. 2.

50 Fig. 6 is a side elevation of the plain or guard ring, and Fig. 7 a sectional view thereof on the line 7—7 of Fig. 6.

The skeleton ring is made up of an arched setting S of any suitable design and pref-

erably of open or filigree work as shown and 55 preferably carrying a stone or other ornament, such as is ordinarily used in an engagement ring, as indicated at O. Integral with the arched setting S and forming the arms thereof I provide two parallel rings 60 indicated at R, spaced apart a suitable distance to receive between them the plain ring and having suitable means such as annular ribs 1 for retaining the plain ring in position between said rings R.

65 Rings R, when constructed of any size, shape and material suitable for such use, will have sufficient resilience to permit the forcing of the plain ring past ribs 1 and into position therewithin as shown in detail 70 at Figs. 3, 4 and 5, where the rings R are shown in normal position which, it is obvious, they resume by virtue of their resilience as soon as the plain ring has passed within ribs 1.

75 The plain ring G may be an ordinary wedding ring of half-round section as also seen in Fig. 5, and preferably corresponds with the contour of the rings R although in practice its opening may be a trifle smaller than the openings through said rings R so that the plain ring will fit the finger rather snugly and also serve as a guard. The setting S arches over the upper side of the ring 80 for any desired portion of its circumference 85 commonly about one third, as perhaps best seen in Fig. 2. The particular design of the setting and the arrangement of its gem-holding devices are not important matters in the present specification so long as this setting 90 arches said space at the upper side of the ring only, leaving it possible to insert the plain or guard ring G from beneath.

95 In this connection, however, it should be noted that the construction herein described and illustrated in the drawings, renders possible and practical a very pleasing and desirable effect, namely, that of an outer skeleton ring of material of one color such as platinum, having a plain ring of another 100 color, such as gold, set within the skeleton ring and visible through the open-work thereof. Thus an artistic combination of engagement ring and wedding ring may be produced or either ring may be worn separately.

105 It will be noted that many details of construction, as for instance the particular

means as ribs 1, for holding the plain ring within the skeleton, may be varied without departing from the spirit of the invention.

What I claim is:

- 5 1. A composite article of jewelry consisting of a complete ring comprising two bands having retaining means forming concave seats standing in parallel planes and yieldingly separable at one side of the ring,
- 10 10 a connecting display portion between said bands at the opposite side of the ring, and a separable, complete finger ring interposed, from opposite said portion, between said bands and axially alining with them when 15 in place between said means.
- 15 2. A finger ring comprising a setting at one side, a pair of axially spaced laterally yieldable bands depending from said setting, and a detachable ring insertible from 20 opposite said setting and filling the peripheral space between said bands, its opening registering with the openings in the bands when it is in place, said bands yielding as the latter ring is inserted.
- 25 3. A finger ring comprising a display portion at one side, a pair of axially spaced bands connected thereto and a detachable ring insertible from opposite the display portion and filling the peripheral space between said bands, its opening registering with the openings in the band when it is in place.
- 30 4. A finger ring comprising two axially

spaced bands with their inner faces having opposed annular, parallel concave seats, means connecting the bands at one side of the ring, and a detachable finger ring interposed from the opposite side of the ring and exposed between said bands and held in said seats.

35 5. An article of jewelry consisting of an ornamenteally complete finger ring comprising two substantially parallel bands of flexible material integrally connected at one side and adapted to yieldingly separate at 40 the diametrically opposite sides, and another ornamenteally complete finger ring between said bands and axially alining with them when in place and being visible between said bands.

45 6. A finger ring having its annulus circumferentially divided into connected yieldable bands with shoulders on their inner faces and opposite the connection constituting seats for yieldingly retaining a complementary removable ring,

50 7. An integral, ornamenteally complete finger ring having interior, annular, parallel co-axial, concave seats yieldingly connected by a display portion at one side of the ring and adapted to relatively separate at the opposite side of the ring to receive and axially aline with an insertible ring.

In testimony whereof I affix my signature.

KARL ZACK.
